8 Claims. (Cl. 74—150)

1

This invention relates to apparatus for automatically operating the driving members of washing and like machines.

Washing machines comprise members which are put into operation at certain determined moments of the washing cycle, such as for example inlet, outlet and heating valves, shutters, members which distribute the washing and other products, and members which drive the motor of the washing machine. In known machines these different members are operated manually or automatically by means of different systems, making use of drums, discs, chains, or cam shafts, connected by mechanical or other means with interrupters, valves or relays. In all cases the duration of the operations is determined by the speed of travel of the discs, drums or other elements.

The present invention is based on the fact that in the course of washing and laundering, the operations to be carried out can be divided into two groups, viz, those which are repeated in a certain order for each of the successive baths, and those which are repeated for each batch, that is, those which regulate the succession and the quality of the baths.

The invention consists of an apparatus for automatically driving the washing machines, composed of two units, one of which comprises the drive for the members the operations of which are repeated at each bath, and the other which comprises the members the operations of which are repeated with each batch or charge.

According to one feature of the present invention, one of the units acts upon the other and vice versa, that is, when one of the units has stopped, the other passes through a certain phase of its cycle, and inversely. In one modification a unit relating to the drive of the members to be operated consists of ratchet wheels operated by pawls carried on a pivoting arm and of a locking plate. The construction is such that the plate of one group acts upon the pawls of the other group, in this way the movement of one unit is determined by the movement of the other. The ratchet wheels of one unit influence cams which drive the members to be operated and the locking plate, with hollows and raised portions, which eventually raise the pawls of the other unit. The pawls of each unit are carried by an arm which is driven in an alternative movement by an exterior driving source. One of the plates determines the number and duration of each successive bath, and consequently the duration of each batch; the other plate prevents a bath from

2

starting at an unsuitable moment, as for instance with the emptying or filling members open.

According to an embodiment there are two ratchet wheels for each unit, one, being that of reduction, determining the speed of advancement of the other, the driving wheel secured to the shaft which carries the cams driving the members to be operated. Moreover, each pawl plate of each group comprises four pawls or rollers engaging the reducing ratchet wheel, the driving wheel, the locking plate and one plate for simultaneously raising the two pawl plates, respectively. The arrangement is completed by the addition of ratchets which prevent the backward movement of the reduction wheel and driving wheel.

Other details will become evident from the description with reference to the accompanying drawings, which are given by way of illustration, 20 of embodiments of the invention.

In the accompanying drawings:

Figure 1 is a perspective view of one arrangement according to the invention, and

Figure 2 is a longitudinal cross section of a 25 modified arrangement.

As shown in Figure 1, an arm 2 mounted on an axle 3 has imparted thereto a to-and-fro movement. On this arm is mounted a rod 4 which carries two pawl plates 5 and 6 having several pawls or rollers. The pawl plates can be raised either both together by a general stopping plate 7, which is operated by raising the handle when it is desired to stop or suspend the progress of the washing operation, or else each plate can be raised separately by two locking plates 9 and 10. The pawl plates 5 and 6 are each provided with four pawls 5', 5'', 5''' and 5''', and 6', 6'', 6''' and 6''''' respectively. The contacting points of the pawls may comprise a roller.

When the pawl plates are in the lowered position, the pawls operate ratchet toothed wheels 11 and 12 loosely mounted on co-axial shafts 3 and 13. Each of these wheels 11 and 12 has one or more deeper teeth than the others, allowing the pawl to fall further and to drive by means of the pawls 5'' and 6'' driving ratchet wheels 14 and 15 which are secured to the shafts 3 and 13 respectively on which are also secured driving cams for operating the members or apparatus to be driven.

The first unit which relates to the operations which are repeated for each bath comprises the driving wheel 14 secured to the shaft 3, the reducing wheel 11, the locking plate 10 secured to the

shaft 3 and the various cams such as 16 for driving the operating members.

The second unit which relates to the operations which are repeated at each batch comprises the driving wheel 15 secured to the shaft 13, the reducing wheel 12, the locking plate 9 secured to the shaft 13 and the various cams such as 17. Both units are supported on a frame 18.

Various pawls 11', 14', 12' and 15' are mounted on a shaft 19 and prevent backward movement of the ratchet wheels during the backward movement of the arm 2.

The apparatus functions as follows: At the start of the first bath, the articles to be washed being in the machine and the motor stopped, the pawl 5''' of the pawl plate 5 is engaged in a notch in the plate 9. The pawl 6''' of the pawl plate 6 is in the low position in the hollow of the plate 10, but is only a short distance from a raised portion of plate 10 as shown in Figure 1.

As soon as the motor is started, the reduction wheel 11, at each deep tooth causes the wheel 14 to advance by one tooth, because if pawl 5' penetrates into a deep tooth, pawl 5''' can drive wheel 14. The shaft 3 rotates and the plate 10 raises the pawl plate 6, pawl 6''' having reached the raised portion on plate 10. The cams 16 have operated their members and have, for instance, closed the outlet, tilted the washing container, etc. When the shaft 3 has made one revolution under the influence of wheel 14, a hollow part on the plate 10 has again arrived in front of the pawl 6''' of the pawl plate 6. This, by means of pawl 6' operates the wheel 12 which, having only one deep tooth causes the wheel 15 to advance by one tooth per revolution.

As soon as the wheel 15 has advanced by one tooth, a raised portion of the plate 9 raises the pawl 5''' of the pawl plate 5; and the pawl 5' is disengaged from the wheel 11, the movement of which is stopped.

The plate 9 has distributed over its periphery a series of hollows which limit the duration of the different baths.

It is clear that if two successive hollows of the plate 9 are displaced at an angle corresponding to that of a given number of teeth of the wheel 15, the duration of the bath is that of a number of revolutions of the wheel 12, increased by the duration of time during which the plate 10 has raised the pawl plate 6.

This last period is that of two revolutions of the wheel 11, if this one has one deep tooth to every three; it would be that of three revolutions, if there were one deep tooth to every four, and so on, providing that in any case the notch in the plate 10 is equal to the third, quarter, etc. respectively of a circumference.

On the whole, then, supposing two hollows in the plate 9 being displaced by five teeth, the duration of the bath is that of two revolutions of the wheel 11, increased by that of five revolutions of the wheel 12.

The plates 9 and 10 and the pawls 5''' and 6''' of the pawl plates have to be designed and constructed so as to avoid that when the arm 2 moves back, the pawl does not come in front of the tooth of the plate, and causes the ill-timed advancing of the plate, and with it of the remainder of the mechanism.

It is also clear that if the plate 9 has a longer hollow, enlarged, for instance, by one division, the wheel 14, and consequently all the cams of the first, will make two successive revolutions,

i. e. they will make the bath last at least three revolutions of the wheel 11, followed immediately by a second one. This property can be applied, for instance, to produce several rinsings successively of a minimum duration.

Figure 2 shows a modified embodiment. In this figure the same reference numbers are used as those in Figure 1 to indicate the same or similar parts. The parts constituting the first unit comprise, as in Figure 1, the reduction wheel 11, the driving wheel 14 and the plate 10 secured to the shaft 3 which carries the cams 16 which operate the members to be driven (not shown). On the rod 4 is mounted the pawl plate 5 formed of two parts, that is having the pawl 5''' separated from the others. This pawl 5''' comes in contact with the plate 9 secured to the shaft 13, in the same way as the wheel 15 and the cams 17. Between the plate 9 and the cams 17 there is a plate 9' which is acted upon by a pawl 20. This plate 9' is toothed only on that part of the periphery which corresponds to the divisions which 9 will still have to cover to finish a complete revolution after the various baths have terminated.

If, for instance, it has 10 teeth, when the wheel 15, advancing by one tooth only, reaches the toothed portion of 9', the plate 9 again begins to move; after ten movements of the arm 2, that is, after ten seconds, it brings its first notch under the pawl 5''' of the pawl; the wheel 14 turns and one of the cams 16 operates the members for emptying the container, the batch is finished.

According to one characteristic of the construction shown in Figure 2, the locking plate 9 and the cams 17 are mounted at one end of the shaft, so that they can be easily exchanged for other similar elements if it is desired to change the process of washing.

What I claim is:

1. A multiple stage containing program control mechanism comprising two groups of rotating cams, two groups of ratchet wheels for respectively rotating said cams, two pawl plates for operating said two groups of ratchet wheels, a notched locking plate associated with each group of ratchet wheels, the locking plate of one group acting upon the pawls of the other group and inversely in such a way that the operation of one group causes the other group first to stop and then to be again operated, said other group causing then the one said group to stop, each said group of ratchet wheels comprising a speed reducing wheel and a driving wheel, the speed reducing wheels being so designed that the cams of one of said groups make a rotation during the duration of each stage and the cams of the other group make a rotation during the program.

2. A multiple stage containing program control mechanism comprising two groups of rotating cams, two groups of ratchet wheels for respectively rotating said cams, two pawl plates for operating said two groups of ratchet wheels, a notched locking plate associated with each group of ratchet wheels, the locking plate of one group acting upon the pawls of the other group and inversely in such a way that the operation of one group causes the other group first to stop and then to be again operated, said other group causing then the one said group to stop, each said group of ratchet wheels comprising a speed reducing wheel and a driving wheel, the speed reducing wheels being so designed that the cams of one of said groups make a rotation during the

duration of each stage and the cams of the other group make a rotation during the program and an arm having a to and fro movement for operating said pawl plates.

3. A multiple stage containing program control mechanism comprising two groups of rotating cams, two groups of ratchet wheels for respectively rotating said cams, two pawl plates for operating said two groups of ratchet wheels, a notched locking plate associated with each group of ratchet wheels, the locking plate of one group acting upon the pawls of the other group and inversely in such a way that the operation of one group causes the other group first to stop and then to be again operated, said other group causing then the one said group to stop, each said group of ratchet wheels comprising a speed reducing wheel and a driving wheel, the speed reducing wheels being so designed that the cams of one of said groups make a rotation during the duration of each stage and the cams of the other group make a rotation during the program and an arm having a to and fro movement for operating said pawl plates, said pawl plates having three pawls, one of which acts upon said speed reduction wheel, another pawl acting upon the driving wheel and the third pawl of a plate acting upon the locking plate of the other group and inversely.

4. A multiple stage containing program control mechanism comprising two groups of rotating cams, two groups of ratchet wheels for respectively rotating said cams, two pawl plates for operating said two groups of ratchet wheels, a notched locking plate associated with each group of ratchet wheels, the locking plate of one group acting upon the pawls of the other group and inversely in such a way that the operation of one group causes the other group first to stop and then to be again operated, said other group causing then the one said group to stop, each said group of ratchet wheels comprising a speed reducing wheel and a driving wheel, the speed reducing wheels being so designed that the cams of one of said groups make a rotation during the duration of each stage and the cams of the other group make a rotation during the program and an arm having a to and fro movement for operating said pawl plates, said pawl plates having three pawls, one of which acts upon said speed reduction wheel, another pawl acting upon the driving wheel and the third pawl of a plate acting upon the locking plate of the other group and inversely, an additional cam associated with each group of ratchet wheels and an additional pawl associated with each pawl plate for simultaneously raising said pawl plates.

5. A multiple stage containing program control mechanism comprising two groups of rotating cams, two groups of ratchet wheels for respectively rotating said cams, two pawl plates for operating said two groups of ratchet wheels, a notched locking plate associated with each group of ratchet wheels, the locking plate of one group acting upon the pawls of the other group and inversely in such a way that the operation of one group causes the other group first to stop and then to be again operated, said other group causing then the one said group to stop, each said group of ratchet wheels comprising a speed reducing wheel and a driving wheel, the speed reducing wheels being so designed that the cams of one of said groups make a rotation during the duration of each stage and the cams of the other group make a rotation during the program and

an arm having a to and fro movement for operating said pawl plates, said pawl plates having three pawls, one of which acts upon said speed reduction wheel, another pawl acting upon the driving wheel and the third pawl of a plate acting upon the locking plate of the other group and inversely, an additional cam associated with each group of ratchet wheels and an additional pawl associated with each pawl plate for simultaneously raising said pawl plates, a shaft for each group of ratchet wheels on which are mounted said cams, the said shafts being co-axial.

6. A multiple stage containing program control mechanism comprising two groups of rotating cams, two groups of ratchet wheels for respectively rotating said cams, two pawl plates for operating said two groups of ratchet wheels, a notched locking plate associated with each group of ratchet wheels, the locking plate of one group acting upon the pawls of the other group and inversely in such a way that the operation of one group causes the other group first to stop and then to be again operated, said other group causing then the one said group to stop, each said group of ratchet wheels comprising a speed reducing wheel and a driving wheel, the speed reducing wheels being so designed that the cams of one of said groups make a rotation during the duration of each stage and the cams of the other group make a rotation during the program and an arm having a to and fro movement for operating said pawl plates, said pawl plates having three pawls, one of which acts upon said speed reduction wheel, another pawl acting upon the driving wheel and the third pawl of a plate acting upon the locking plate of the other group and inversely, an additional cam associated with each group of ratchet wheels and an additional pawl associated with each pawl plate for simultaneously raising said pawl plates, a shaft for each group of ratchet wheels on which are mounted said cams, the said shafts being parallel.

7. A multiple stage containing program control mechanism comprising two groups of rotating cams, two groups of ratchet wheels for respectively rotating said cams, two pawl plates for operating said two groups of ratchet wheels, a notched locking plate associated with each group of ratchet wheels, the locking plate of one group acting upon the pawls of the other group and inversely in such a way that the operation of one group causes the other group first to stop and then to be again operated, said other group causing then the one said group to stop, each said group of ratchet wheels comprising a speed reducing wheel and a driving wheel, the speed reducing wheels being so designed that the cams of one of said groups make a rotation during the duration of each stage and the cams of the other group make a rotation during the program and an arm having a to and fro movement for operating said pawl plates, said pawl plates having three pawls, one of which acts upon said speed reduction wheel, another pawl acting upon the locking plate of the other group and inversely, an additional cam associated with each group of ratchet wheels and an additional pawl associated with each pawl plate for simultaneously raising said pawl plates, a shaft for each group of ratchet wheels on which are mounted said cams the said shafts being coaxial, the locking plate of one said group as well as the group of cams associated therewith being removably mounted at one end of said one shaft.

8. A multiple stage containing program control mechanism comprising two groups of rotating cams, two groups of ratchet wheels for respectively rotating said cams, two pawl plates for operating said two groups of ratchet wheels, a notched locking plate associated with each group of ratchet wheels, the locking plate of one group acting upon the pawls of the other group and inversely in such a way that the operation of one group causes the other group first to stop and then to be again operated, said other group causing then the one said group to stop, each said group of ratchet wheels comprising a speed reducing wheel and a driving wheel, the speed reducing wheels being so designed that the cams of one of said groups make a rotation during the duration of each stage and the cams of the other group make a rotation during the program and an arm having a to and fro movement for operating said pawl plates, said pawl plates having three pawls, one of which acts upon said speed reduction wheel, another pawl acting upon the locking plate of the other group and inversely, an additional cam associated with each group of

5 ratchet wheels and an additional pawl associated with each pawl plate for simultaneously raising said pawl plates, a shaft for each group of ratchet wheels on which are mounted said cams, the said shafts being coaxial, the locking plate of one said group as well as the group of cams associated therewith being removably mounted at one end of said one shaft and an auxiliary plate associated with said removable locking plate for moving said locking plate back to zero.
